(57) **CLAIM**

The ornamental design of a neck traction apparatus, as shown and described.

DESCRIPTION

FIG. 1 is a perspective view of the neck traction apparatus; FIG. 2 is a front elevation view of the neck traction apparatus;

FIG. 3 is a right side elevation view of the neck traction apparatus, the left elevation side being a mirror image thereof;

FIG. 4 is a rear elevation view of the neck traction apparatus;

FIG. 5 is a top plan view of the neck traction apparatus;

FIG. 6 is a bottom plan view of the neck traction apparatus;

FIG. 7 is a perspective view of a second embodiment of the neck traction apparatus;

FIG. 8 is a front elevation view of the second embodiment of the neck traction apparatus;

FIG. 9 is a right side elevation view of the second embodiment of the neck traction apparatus, the left elevation side being a mirror image thereof;

FIG. 10 is a rear elevation view of the second embodiment of the neck traction apparatus;

FIG. 11 is a top plan view of the second embodiment of the neck traction apparatus; and,

FIG. 12 is a bottom plan view of the second embodiment of the neck traction apparatus.

The broken lines in FIG. 1 setting forth a hanger and accompanying chain and the broken lines showing the connecting rings and post as seen in FIGS. 7 through 12 are for illustrative purposes only and form no part of the claimed design.
